UNITED STATES PATENT OFFICE.

LLOYD DE WITT SMITH, OF DETROIT, MICHIGAN.

COAL-MAGAZINE FOR AUTOMATIC STOKERS.

No. 848,861.

Specification of Letters Patent.

Patented April 2, 1907.

Application filed October 14, 1905. Serial No. 282,708.

To all whom it may concern:

Be it known that I, LLOYD DE WITT SMITH, a citizen of the United States of America, residing at Detroit, in the county of Wayne and State of Michigan, have invented certain new and useful Improvements in Coal-Magazines for Automatic Stokers, of which the following is a specification, reference being had therein to the accompanying drawings.

10 This invention relates to improvements in automatic stokers, and more especially to improvements in the construction of the coal-magazines for side-feed stokers, the object of the invention being to so construct the magazine that its inclined bottom may be quickly and easily removed for the purpose of replacing or repair without stopping the operation of the furnace and may be as quickly slipped into place, where it will be firmly held without the necessity of bolts or other fastening means.

15 It is also an object of the invention to provide a cast bottom plate which is very rigid, strong, and durable and to provide the same with certain other new and useful features, all as hereinafter more fully described, reference being had to the accompanying drawings, in which—

20 Figure 1 is a perspective view of a magazine embodying the invention with parts broken away to show the construction and showing the same in operative position within a furnace. Fig. 2 is an enlarged horizontal section through the magazine detached from furnace, above the bottom plate, with the arch-plate removed. Fig. 3 is a transverse vertical section through the magazine, looking toward the front end thereof. Fig. 4 is a similar view looking toward the rear end, 25 and Fig. 5 is a detail showing the end walls of the magazine in vertical section with the bottom plate in position thereon.

25 As shown in the drawings, 1 represents the furnace-arch supported upon the arch-plate 2, which also forms the inner side of the coal-magazine 3. Beneath the magazine and its discharge opening or mouth is the coking-plate 4, against which the inclined grate-bars 5 rest at their upper ends and upon which the stoker-boxes 6 are moved laterally by a rock-shaft 7 mounted in bearings beneath the boxes and provided with segments 8, extending upward in the boxes into engagement with racks 9 thereon, all of these parts being 30 constructed and arranged in an old and well-known manner.

The coal-magazine consists of a top plate 10, provided with an opening through which coal may be introduced into the magazine either mechanically or by hand, the vertical 60 cast back wall 11, the rear end wall or casting 12, the front end casting 13, and the inclined bottom plate 14. The furnace-front 15 is provided with a door 16 opposite the open forward end of the magazine, through which 65 door the operator may view the interior of the magazine or may introduce coal.

The inclined bottom plate 14 is subjected to extreme heat, and therefore is liable to be burned out or warped, and this is especially 70 true when the bottom is made of more than one part or a triangular bottom-supporting bar and a light plate supported by said bar. It is necessary that the bottom be stiff and heavy enough so that when subjected to extreme 75 heat and the weight of the coal in the magazine it will not sag or bend and by contacting the stoker-boxes prevent their free movement. For this reason I prefer to use a heavy cast plate which is formed with a 80 heavy longitudinally-extending rib 17, extending at right angles to its lower side near its lower edge and together with said edge of the plate forming a triangular-shaped strengthening edge. Transverse webs 18 at 85 intervals throughout the length of the plate connect said rib and plate and further strengthen the bottom.

It is very desirable that the bottom plate be so made and held in place in the magazine 90 that it may be quickly and easily removed for the purpose of repair or replacing without the necessity of taking the furnace apart or even stopping its operation, and therefore it is supported at its ends in bearings on the end 95 walls of the magazine, from which bearings it may be readily lifted and drawn out through the door in the furnace-front. Upon the rear end of the plate at its lower edge is a triangular-shaped projection or lug 19 to engage a 100 recess 20 of similar form in the rear end wall 12, said recess being formed somewhat larger than the lug to permit the lug to turn slightly therein when the plate is tilted, as shown in dotted lines in Fig. 4, to disengage its upper 105 edge from beneath an inwardly-projecting shoulder 21 on the back wall 11, the plate when in place normally resting along its upper edge upon an inwardly-extending inclined flange 22 on said back wall with said 110 edge beneath the shoulder. An inclined rib 23 is provided on the rear end wall to engage

the lower side of the plate at its rear end. In the front end casting 13 is formed a pocket 24 to receive the projecting end of the bottom plate, the bottom 25 of the pocket forming a seat for the plate, the end of which is formed with a laterally-extending web or end flange. 26, which when the plate is in place forms a horizontal face or bearing to engage the bottom of the pocket and fits between the side 10 walls of the pocket to prevent lateral movement of the plate. The forward wall 27 of the pocket is inclined from the open top of the pocket downward and inward and the end of the bottom plate is similarly formed, 15 so that in inserting the plate when it is pushed in through the door and drops into the pocket the inclined side will force the plate longitudinally and engage the lug 19 on its rear end with the recess in the rear end 20 wall. A wide flange or ledge 28, formed at the upper end of the end casting 13, extends forward to the door-opening in the furnace-front, and a downwardly-extending triangular-shaped end flange 29 projects outward 25 from that portion of the end of the bottom plate which extends above the ledge when the plate is in place and engages the upper surface of said ledge. In this flange 29 is a hole 30 for the insertion of a bar by means of 30 which the plate may be lifted or pried from beneath the shoulder 21, the same turning upon its lower edge or point within the pocket at its forward end and upon the corner of its lug within the recess at its rear end 35 and may then be lifted at its forward end and drawn out through the door-opening. The end casting 13 is cut away from its lower side upward into the pocket a short distance, so that the rock-shaft, with its segments, may be 40 removed endwise through an opening 31 in the furnace-front, which opening is closed by a suitable plate.

Having thus fully described my invention, what I claim is—

45 1. In a magazine for automatic stokers, the combination with a side wall, of ends provided with bearings, and a cast bottom plate provided with a longitudinal rib extending from the lower surface of the plate at 50 right angles thereto and at a short distance from one edge thereof to form with said edge a triangular-shaped strengthening edge and having a series of transverse webs connecting the plate and rib and formed with projections on the ends of the plate to engage the 55 bearings and support the plate at each end.

2. In a magazine, for automatic stokers, the combination with a side wall, of a rear end wall formed with a bearing, a front end 60 wall formed with a pocket open at the top and side, a plate adapted to form an inclined bottom for the magazine engaging the pocket at its forward end and provided with means on the rear end of the plate to engage the 65 bearing.

3. In a magazine for automatic stokers, the combination with a side wall, of a rear end wall formed with a recess, a front end wall formed with a pocket open at its top and side, and a plate adapted to engage the 70 pocket at its forward end and provided with a lug on its rear end to engage the recess.

4. In a magazine for automatic stokers, the combination with a side wall, of an inclined bottom plate having a lug on its rear 75 end, a rear end wall provided with a recess to receive said lug, and a front end casting formed with a pocket open at its top and side to receive the forward end of the plate by inserting the same through the open top, said 80 pocket being formed with a front wall which is inclined inward and downward from the top of the pocket to engage the end of the plate.

5. In a magazine for automatic stokers, 85 the combination of a side wall provided with an inwardly-projecting shoulder, a rear end wall formed with a recess, a front end formed with a pocket, and a bottom plate provided with a lug at its rear end to engage 90 and turn in the recess and adapted to engage the pocket at its forward end and be supported with its upper edge beneath the shoulder.

6. In a magazine, for automatic stokers, 95 the combination with a side wall, of a rear end wall formed with a recess, a front end wall formed with a pocket open at the top and one side, and a bottom plate adapted to be supported in an inclined position having a 100 lug on its rear end to engage said recess and a laterally-extending end flange on its forward end to fit within the pocket and engage the side walls thereof when the plate is in its normal position, to prevent lateral movement of 105 the plate.

7. In a magazine for automatic stokers, the combination of a side wall formed with an inwardly-projecting shoulder and an inwardly and downwardly extending longitudinal flange, an end wall formed with a recess, a front end wall formed with a pocket open at its top and side and formed with a front wall extending inward and downward from the top of the pocket, and a bottom 115 plate adapted to engage the flange on the side wall beneath the shoulder and formed with an inwardly and downwardly inclined end to engage the inclined wall of the pocket and with a lug on its rear end to engage and turn within the recess.

8. In a magazine for automatic side-feed stokers, the combination with a furnace-front having a door, of a vertical side wall formed with a longitudinally-extending 125 supporting-flange, a rear end wall formed with a triangular-shaped recess, a front end casting extending upward to the bottom of the door in the furnace-front and formed with a pocket open at its top and inner side 130

and having a front wall extending inward and downward from the upper edge of the casting and provided with a forwardly-extending ledge on its upper end, and an inclined detachable bottom plate having a lug on its rear end to engage the recess in the end wall and a laterally-extending flange on its forward end to fit within the pocket and provided with a forwardly-projecting and

downwardly-extending flange on its forward end at its upper edge to engage and rest upon the ledge.

In testimony whereof I affix my signature in presence of two witnesses.

LLOYD DE WITT SMITH.
